(57) **CLAIM**

The ornamental design for an electrical circuit component, as shown and described.

DESCRIPTION

FIG. 1 is an upper perspective view of the electrical circuit component of the present invention;

FIG. 2 is a lower perspective view of the electrical circuit component of the present invention;

FIG. 3 is a front elevational view of the electrical circuit component of the present invention;

FIG. 4 is a rear elevational view of the electrical circuit component of the present invention;

FIG. 5 is a left side elevational view of the electrical circuit component of the present invention;

FIG. 6 is a right side elevational view of the electrical circuit component of the present invention;

FIG. 7 is a top plan view of the electrical circuit component of the present invention; and,

FIG. 8 is a bottom plan view of the electrical circuit component of the present invention.
